UNITED STATES PATENT OFFICE.

GUSTAV A. ZILLGITT, OF MILWAUKEE, WISCONSIN.

REINFORCED-CONCRETE POST OR POLE.

1,052,990.

Specification of Letters Patent. Patented Feb. 11, 1913.

Application filed May 10, 1912. Serial No. 696,410.

To all whom it may concern:

Be it known that I, GUSTAV A. ZILLGITT, citizen of the United States of America, residing at Milwaukee, in the county of Milwaukee and State of Wisconsin, have invented certain new and useful Improvements in Reinforced-Concrete Posts or Poles, of which the following is a specification.

This invention relates to certain new and useful improvements in reinforced concrete posts or poles; the object being to provide a post or pole with a skeleton upper portion and a base portion having threads for forcing its way into the ground; said base having a core embedded therein carrying reinforcing rods extending into the skeleton upper portion and the main object of the invention is to provide novel means for connecting these reinforcing rods to the core.

Other and further objects and advantages of the invention will be hereinafter set forth and the novel features thereof defined by the appended claim.

In the drawings—Figure 1, is a side elevation of a post or pole, constructed in accordance with my invention; Fig. 2, is a perspective view of the reinforced core and wires upon which the plastic post is molded in order to form a skeleton post or pole as shown in Fig. 1; Fig. 3, is a horizontal section taken on the line 3—3 of Fig. 1; Fig. 4, is a horizontal section taken on the line 4—4 of Fig. 1; Fig. 5, is a longitudinal section taken on the line 5—5 of Fig. 1; Fig. 6, is a side elevation of a post or pole showing a slightly modified form; Fig. 7, is a longitudinal section through the base portion of the modification shown in Fig. 6; Fig. 8, is a section taken on the line 8—8 of Fig. 7; and Fig. 9, is a longitudinal section partly in elevation of still another modified form.

In carrying out my improved invention, I employ a cylindrical core portion 1 which is provided with a longitudinal bore 2 at its upper portion, and the outer face thereof is provided with longitudinal grooves 3 in which are embedded vertical rods 4 secured in position by bands 5 encircling the base or core 1, and seated in the annular grooves 6 as clearly shown; said bands 5 being coiled about the vertical rods 4 as shown at 7 in order to prevent the same from moving longitudinally thereon. The core herein shown is substantially conical in shape in order to produce a base substantially conical so that the same can be readily forced into the

ground by rotating the post. The vertical rods 4 converge toward a common center at their upper ends and are connected together at intervals by horizontal reinforcing wires 60 8 which are coiled about the rods as shown at 9. From the above description it will be seen that I have provided a reinforcing member which comprises a base portion having vertical reinforcing wires carried thereby, connected together at intervals, which can be readily placed in a suitable mold for forming a complete post or pole as will be later described.

A reinforcing member constructed as above described in forming a complete post, is placed within a suitably formed mold and concrete or cement is placed within the same, the same entering the bore of the base and completely covering the reinforcing 75 wires so as to form a skeleton upper portion 10, which comprises parallel members 11 connected together at intervals by horizontal portions 12, said members terminating in a circular portion 13 forming the cap or top 80 of the post, which provides means for connecting the hitching strap, when a post constructed in this manner is used as a hitching post. The cylindrical base or core is also covered with cement, which forms a conical 85 base 14 for the post or pole, provided with a spiral rib 15 forming a thread by means of which the post can be forced into the ground without digging a hole therefor; thereby enabling the post to be set up quickly and 90 moved from place to place, as desired.

In the modification shown in Figs. 6, 7 and 8, the base 14 thereof is cylindrical and of the same diameter throughout its length and comprises a cylindrical core 16 having 95 open ends over which the coating of plastic material is arranged, in substantially the same manner as that shown in the preferred form. In the modification shown in Figs. 6, 7 and 8, it will be seen that the base thus 100 formed is provided with a central opening throughout its length through which the earth in which the post is embedded is adapted to be forced upwardly as the auger base is screwed into position, thereby providing a base of the same diameter throughout its length which can be readily forced into the ground and one which will support the pole firmly.

In the modification shown in Fig. 9, the 110 core 17 is conical or has a smaller lower end which I have found will have advantages

over a post constructed as described in Figs. 6, 7 and 8, when working in exceptionally hard ground and in this figure, the base of the post is also hollow throughout its length in order to allow the ground to work up through the same when being forced into position.

From the foregoing description it will be seen that I have provided a reinforced concrete post or pole having a threaded base portion and a skeleton upper portion which is exceedingly strong and durable, the vertical members thereof being connected at intervals to prevent spreading. By this construction, a great saving of cement is obtained, and at the same time a post is formed which will have all of the advantages of cement posts now in use, the same being capable of being used for various purposes.

20 I claim:

A reinforced concrete post or pole having

a skeleton upper portion and a cylindrical base portion, a hollow cylindrical member embedded in the base portion provided with longitudinal grooves and transverse annular grooves, rods arranged within the longitudinal grooves, wires or bands encircling said base within the annular grooves for securing said rods in the longitudinal grooves, said rods converging toward each other and connected together at intervals by horizontal tie rods, each tie rod being looped around the vertical rods, said core and rods having a coating thereon of concrete to form a concrete post having a skeleton upper portion. 25 30 35

In testimony whereof I affix my signature in presence of two witnesses.

GUSTAV A. ZILLGITT.
